[57] CLAIM

The ornamental design for a piece of body piercing jewelry, as shown and described.

DESCRIPTION

FIG. 1 is a perspective view of a piece of body piercing jewelry showing my new design;

FIG. 2 is a top view of FIG. 1;

FIG. 3 is a left side elevation view of FIG. 1, the right side being a mirror image;

FIG. 4 is a front view of FIG. 1;

FIG. 5 is a bottom view of FIG. 1;

FIG. 6 is a perspective view of a second embodiment of the design of FIG. 1;

FIG. 7 is a top view of FIG. 6;

FIG. 8 is a left side elevation view of FIG. 6, the right side being a mirror image;

FIG. 9 is a front view of FIG. 6;

FIG. 10 is a bottom view of FIG. 6;

FIG. 11 is a perspective view of a third embodiment of the design of FIG. 1;

FIG. 12 is a top view of FIG. 11;

FIG. 13 is left side elevation view of FIG. 11, the right side being a mirror image;

FIG. 14 is a front view of FIG. 11; and,

FIG. 15 is a bottom view of FIG. 11.
